FIRE-VENT BUILDING

Arthur L. Brown, Boston, Mass., assignor to
 Factory Mutual Research Corporation, Boston,
 Mass., a corporation of Massachusetts

Application December 6, 1945, Serial No. 633,216

8 Claims. (Cl. 108—1)

1

The spread of fire in a building is often caused by the heat which rises from a localized fire striking a ceiling or a roof and then spreading laterally. It has been proposed to have automatic ventilators in a roof to open in response to a fire, permitting the escape of the heat through an opening in the roof and thereby delaying the spread of the fire. However these automatic ventilators have not been satisfactory for various reasons. They require fusible links and other mechanism which is more or less in the way and which tends to get out of order. Moreover the ventilators frequently stick owing to the fact that they need to be opened only at rare intervals.

Objects of the present invention are to provide a construction which not only provides a vent opening automatically in response to a fire but which requires no fusible links or other mechanism, which can not fail to function due to sticking, which can easily be made weatherproof with no tendency to result in a leaky roof, which tends to localize a fire more effectively than do the automatic ventilators of the prior art, and which minimizes water damage in buildings where automatic sprinklers have been installed.

According to the present invention the roof is provided with supporting members of any usual or suitable construction but the covering material has at least a portion of thin fusible sheet material exposed on both sides so that the rising column of heat from a localized fire beneath the roof can quickly form a vent opening to permit the escape of the heat, thereby retarding the spread of the fire, and to allow a rapid removal of smoke, thus facilitating manual firefighting. While the fusible material preferably comprises one or more panels of fusible metal, such as alloys of zinc and tin or alloys of cadmium, zinc, lead and bismuth, it may comprise plastic material which has a low melting point, such as Pliofilm or other rubber composition, natural resins, alkyl resins and asphalts, or which has a low kindling point and is rapidly combustible, such as pyroxylin. Indeed the panels may be translucent so that they also serve to admit light. While the fusing or ignition temperature of the sheet material may be varied to suit different conditions, in most cases the temperature should be 300° F. or lower and in no case should it exceed 700° F. By having the temperature at or below that at which the sprinklers open, widespread water damage is avoided. When an insulating effect is desired two or more sheets of the fusible material may be employed with an air space between each two adjacent sheets so that each sheet is exposed

2

on both sides. In the preferred embodiment fusible sections are disposed at recurrent intervals through the area of the roof and metal fire curtains depend from the roof between the sections to assist in directing the heat to the fusible section immediately above the fire.

For the purpose of illustration typical embodiments of the invention are shown in the accompanying drawings in which

10 Fig. 1 is a perspective view of the invention applied to one type of building;

Fig. 2 is a transverse section through Fig. 1; and

15 Fig. 3 is a view similar to Fig. 1 showing a modification.

The particular embodiment of the invention shown in Figs. 1 and 2 comprises a factory building having side walls 1, end walls 2 provided with windows 3, sloping roof 4, a raised central section 5 provided with windows along the ends and sides and a central roof comprising sheets 6 of the aforesaid fusible material. The sheets 6 are supported on recurrent strips 7 which in turn are supported on longitudinal purlins 8, 9 and 10. 20 The space between the two sides of the central roof may be bridged by an arched strip 11 secured in place by fasteners 12. At recurrent intervals along the roof fire curtains 13 hang down approximately to the bottom of the central section 5.

25 The modification shown in Fig. 3 is similar to that shown in Figs. 1 and 2 except in that the building 14 has a flat roof and instead of the entire roof being covered with fusible sheet material the roof is provided with recurrent openings covered with panels 15 of the fusible sheet material. Each panel may be sealed directly to the roof around its periphery or it may be mounted 30 in a steel frame which in turn is mounted over the edge of the opening in the roof. Fire curtains may be provided not only transversely of the building between each two adjacent transverse rows of panels but also longitudinally of the building between each two adjacent longitudinal rows of panels.

35 From the foregoing it will be understood that in the case of a localized fire the heat will rise to the fusible sheet material immediately above the fire and there form an opening in the roof through which the heat can escape so that the roof will not cause it to spread out to adjacent sections of the building. The modification shown in Fig. 3 has the advantage that when a panel is 40 destroyed the roof may be restored to normal

condition merely by replacing the sheet of fusible material in the one panel.

In buildings using asphalt protected metal or even of completely combustible or, on the other hand, completely noncombustible construction such as corrugated iron on steel frame, the temperatures underneath the roof can be greatly lowered by the proper vents in case of a fire with consequent much reduced spread of fire with combustible materials, or with a greatly reduced chance of weakening the steel supporting members in the case of the structure covered with corrugated iron. Furthermore, manual fire fighting is made easier with these automatic facilities to permit the escape of heat and smoke.

It should be understood that the present disclosure is for the purpose of illustration only and that this invention includes all modifications and equivalents which fall within the scope of the appended claims.

I claim:

1. A building construction comprising a roof having supporting members and covering material at least a portion of which comprises fusible sheet material exposed on both sides so that the rising column of heat from a localized fire beneath the roof can quickly form a vent opening to permit the escape of the heat, thereby retarding the spread of the fire.

2. A building construction comprising a roof having supporting members and covering material at least a portion of which comprises fusible sheet metal exposed on both sides so that the rising column of heat from a localized fire beneath the roof can quickly form a vent opening to permit the escape of the heat, thereby retarding the spread of the fire.

3. A building construction comprising a roof having supporting members and covering material recurrent sections of which comprise fusible sheet material exposed on both sides so that the rising column of heat from a localized fire beneath one of the sections can quickly form a vent opening to permit the escape of the heat, thereby retarding the spread of the fire.

4. A building construction comprising a roof having openings at recurrent intervals and clo-

sures for the openings which comprise fusible sheet material exposed on both sides so that the rising column of heat from a localized fire beneath one of the closures can quickly burn out the closure to permit the escape of the heat through the opening, thereby retarding the spread of the fire.

5. A building construction comprising a roof having supporting members and covering material at least a portion of which comprises fusible sheet material exposed on both sides so that the rising column of heat from a localized fire beneath the roof can quickly form a vent opening to permit the escape of the heat, and a fire curtain depending from the roof adjacent said portion to assist in directing the heat to said portion.

6. A building construction comprising a roof having supporting members and covering material at least a portion of which comprises fusible sheet metal exposed on both sides so that the rising column of heat from a localized fire beneath the roof can quickly form a vent opening to permit the escape of the heat, and a fire curtain depending from the roof adjacent said portion to assist in directing the heat to said portion.

7. A building construction comprising a roof having supporting members and covering material recurrent sections of which comprise fusible sheet material exposed on both sides so that the rising column of heat from a localized fire beneath one of the sections can quickly form a vent opening to permit the escape of the heat, and fire curtains depending from the roof between the sections to assist in directing the heat from the fire to the section thereabove.

8. A building construction comprising a roof having openings at recurrent intervals and closures for the openings which comprise fusible sheet material exposed on both sides so that the rising column of heat from a localized fire beneath one of the closures can quickly burn out the closure to permit the escape of the heat through the opening, and fire curtains depending from the roof between the openings to assist in directing the heat from the fire to the opening thereabove.

ARTHUR L. BROWN.
